UNITED STATES PATENT OFFICE

2,538,169

BOILER UNIT

George Steiner, New Haven, Mich.

Application June 11, 1948, Serial No. 32,381

1 Claim. (Cl. 122—165)

1

This invention relates to fluid heaters, and more particularly to a hot water heater for use as a boiler in a heating system.

A main object of the invention is to provide a novel and improved boiler which is simple in construction, compact in size, easy to maintain, and which utilizes the heat from the heating source with a maximum degree of efficiency, whereby the boiler is very economical in fuel consumption.

A further object of the invention is to provide an improved boiler for use in heating systems and the like, wherein the products of combustion are maintained in close heat-conducting relation to the water chamber, said chamber being arranged in a very compact manner and with maximum exposure to the products of combustion, the boiler being inexpensive to manufacture, rugged in construction, and cheap to operate.

Further objects and advantages of the invention will become apparent from the following description and claim and from the accompanying drawings, wherein:

Figure 1 is a vertical cross-sectional view taken through a boiler constructed in accordance with the present invention.

Figure 2 is another vertical cross-sectional view of the boiler taken on line 2—2 of Figure 1.

Referring to the drawings, the boiler unit comprises a base shell 11 in which is positioned a suitable burner 12, such as an oil burner, the fuel conduits for the burner being shown at 13, 13. Shell 11 is provided with a conventional hinged door 14 and is formed at its top margin with an outwardly projecting flange 15. Designated at 16 is the boiler main housing, said main housing being formed with a bottom flange 17 supported on said flange 15 and secured to flange 15 as by bolts 18.

The housing 16 is generally rectangular in plan and the walls thereof are hollow, defining a water jacket 19. Water jacket 19 extends around the top and sides of housing 16 except for a portion of one side of said housing, at which a door 20 is provided. The water jacket may be considered to be formed of an inner casing open at one end and having its open end resting on base 11 and a second casing surrounding and spaced from said first casing and fixedly secured thereto to form the water jacket 19.

Designated at 21 is a flat vertically rising zig-zag or serpentine water conduit secured within housing 16 and extending for the full internal width thereof. At one side said conduit is secured to an inner wall 22 of the back wall of the

2

water jacket 19. At the other side said conduit is abutted by door 20. The lower end of the conduit 21 is connected to the bottom portion of water jacket 19 by a short pipe section 23. The top end of conduit 21 is connected to the top of the water jacket 19 by another short pipe section 24. Connected to the top of the water jacket 19 are outlet conduits 26, 26, leading to the radiators of the system. Connected to the bottom portion of said water jacket is the cold water return conduit 27.

Secured to the inner walls of the water jacket and coextensive in width with the flat zig-zag conduit 21 are alternating baffle plates 28 extending horizontally in the planes of the respective bends of the conduit 21 but spaced at their inner ends from the bends to provide flue passages 29 for the upwardly flowing gaseous products of combustion generated by the burner 12. Formed integrally with the housing and extending partly in jacket 19 is a flue 30 provided at its top end with a duct portion 31 communicating with the flue space above the top end of the flat water conduit 21. Flue 30 is connected to a flue pipe 32 leading to the smokestack or chimney which provides draft for the burner.

Designated at 33 is a clean-out duct aligned with duct portion 31 and integrally formed in the wall of housing 16. Hinged to the outside of the housing wall is a door 34 normally closing off said clean-out duct.

The bottom door 14 is of the conventional furnace door type provided with vents for the admission of air to the burner. The usual slideable cover plates may be provided for said vents to regulate the amount of air admitted. Duct 32 may be likewise provided with an adjustable flap damper to regulate the draft in the usual manner.

In operation, water in the jacket 19 and in the flat vertically rising zig-zag conduit 21 is heated by the gaseous products of combustion generated by burner 12, said gaseous products travelling upwardly around the conduit 21 on both sides thereof past the inner ends of the alternating baffles 28 to the flue duct 31. The baffle plates 28 guide said gaseous products substantially along the surfaces of the zig-zag conduit, requiring said products to flow through the passages 29 adjacent the inside bends of the conduit. This maintains the gaseous products in close proximity to the surfaces of the conduit and assures efficient transfer of heat from the gases to the water in the conduit. A very large heat transfer area for a given boiler volume is thus provided.

It will be seen from Figure 2 that by opening

the side door 20, access to substantially all of the heat transfer surfaces of the zig-zag water conduit 21 may be obtained. This enables said surfaces to be frequently cleaned so as to maintain them in a highly efficient condition. The ability to readily clean these surfaces makes it possible to operate the boiler economically as to fuel requirements, and also makes it possible to bring the system up to working steam pressure in a very short period of time.

Residual heat in the exhaust gases is transferred to the water in jacket 19 from the portion of flue 30 which extends through said jacket.

While a specific embodiment of a boiler for use in steam heating systems has been disclosed in the foregoing description, it will be understood that various modifications within the spirit of the invention may occur to those skilled in the art. Therefore, it is intended that no limitations be placed on the invention except as defined by the scope of the appended claim.

What is claimed is:

A boiler comprising a base, a casing having one end open positioned with its open end resting upon said base and secured thereto, a burner mounted within said base and in communication with the open end of said casing for generating heated products of combustion, a vertically disposed serpentine conduit positioned within and fixedly secured to the back wall of said casing and bearing against the front wall of the latter and spaced from the opposed side walls of said casing, a second casing surrounding and fixedly secured to said first casing and spaced from the latter to thereby form a water jacket, an inlet adjacent the lower end of said second casing for admitting water to be heated into said jacket,

an outlet in the top of said second casing for withdrawing the heated water from said jacket, a horizontally disposed pipe positioned within said first casing adjacent the lower end thereof and having one end in communication with said jacket and the other end in communication with the lower end of said conduit, a second vertically disposed pipe positioned within and adjacent the upper end of said first named casing and having one end in communication with said jacket and the other end in communication with the upper end of said conduit, a plurality of horizontally disposed baffle plates positioned in opposed spaced vertical relation with respect to each other and fixedly carried by said first named casing and forming with said serpentine conduit a tortuous passage way for the passage of products of combustion therethrough, an outlet flue in communication with the upper end of said first named casing for withdrawing the products of combustion from the first named casing.

GEORGE STEINER.
